UNITED STATES PATENT OFFICE.

JOHN W. GOODENBERGER, OF AKRON, OHIO.

SWIMMER'S FOOT-PADDLE.

1,114,466.

Specification of Letters Patent. Patented Oct. 20, 1914.

Application filed December 23, 1913. Serial No. 808,481.

To all whom it may concern:

Be it known that I, JOHN W. GOODENBERGER, a citizen of the United States, residing at Akron, in the county of Summit 5 and State of Ohio, have invented certain new and useful Improvements in Swimmers' Foot-Paddles; and I do hereby declare the following to be a full, clear, and exact description of the invention, such as 10 will enable others skilled in the art to which it appertains to make and use the same.

My invention relates to improvements in propelling devices for swimmers and resides in the provision of a foot paddle which 15 is adapted to be worn on the swimmer's ankle and will operate to give the drive of the swimmer's legs a greater bearing surface in the water.

An important object of the invention is to 20 provide a paddle of the character described which is secured to the ankle of the wearer by a novel form of securing means and which employs means for holding the paddle normally in an inclined angular position relative to the longitudinal axis of the device whereby the desired operation of the paddle is permitted on the drive stroke of the swimmer's legs.

Another important object of the invention 30 is to provide a device of the character described which is simple as to construction, consists of few parts and which may be cheaply manufactured.

The above and additional objects are accomplished by such means as are illustrated 35 in the accompanying drawings, described in the following specification and then more particularly pointed out in the claims which are appended hereto and form a part of this application.

With reference to the drawings, wherein I have illustrated the preferred embodiment 40 of my invention as it is reduced to practice, and throughout the several views 45 of which similar reference numerals designate corresponding parts: Figure 1 is a side elevation of the device showing the paddle in extended position, Fig. 2 is a perspective view showing the device attached 50 to the foot of the swimmer, Fig. 3 is a perspective view showing the paddle in normal position, Fig. 4 is a top plan view showing the paddle in extended position, and Fig. 5 is a vertical sectional view showing the

spring for holding the paddle in partially 55 extended normal position.

Referring to the drawings by characters of reference the numeral 1 designates as an entirety a rectangular wing or paddle which is provided with an extension ear 2 intermediate the ends and along one longitudinal edge to provide for the hinging of the paddle 1 after a manner which will be later more fully described. The paddle or wing 1 is formed of some suitable type of light 60 sheet metal.

As a means for attaching the paddle 1 to the foot of the swimmer, there has been provided an L-shaped support designated 3 as an entirety. This L-shaped support 3 is 65 formed of some suitable light strap metal and is provided intermediate its longer arm with an approximately U-shaped integral frame designated 4 as an entirety. The body portion of this frame is integral centrally of its ends with the longer arm of the L-shaped support 3 and the frame 4 is disposed at right angles to the longer arm in a horizontal plane. The inner ends of the arms 5 and 6 of the frame 4 are enlarged 70 as at 7 and have inserted centrally therethrough a hinge pin 8 that extends across the frame. The extension 2 on the paddle 1 is recessed centrally of its side edges as at 9 to produce a pair of tongues 10 which 75 are bent about the pin 9 and thus hingedly secure the paddle 1 to the L-shaped support 3.

Mounted on the central portion of the pin 8 is a coil spring 11 having its respective 80 terminals, 12 and 13 disposed for engagement with the longer arm of the L-shaped support 3 and the under face of the paddle 1. The spring 11 is positioned in such a way that the paddle 1 is normally disposed 85 in angular spaced relation to the longer arm of the support 3. It has been found preferable to provide a light spring in this connection so that upon the withdrawing movement or up-stroke of the swimmer's 90 legs the spring will permit inward movement of the paddle 1 relative to the longer arm 3 and thus prevent impeding of the swimmer's 95 movement.

The portion of the longer arm of the L- 100 shaped support 3 which extends above the U-shaped frame 4 is curved outwardly so that when the support 3 is fitted so that the

longer arm is in engagement with the side of the foot, ankle and lower portion of the leg, it conforms to the shape of the leg and provides a reliable and comfortable fitting.

5 This extended curved portion which for the sake of clearness is designated by the numeral 14 is provided with a curved integral and approximately rectangular cross plate 15 which has longitudinal slots 16 in its ends.

10 The cross plate 15 in being curved provides its conformation to the contour of the swimmer's leg. The longitudinal slots 16 in the plate 15 permit the attachment of a suitable securing strap 17 which is secured about the lower portion of the leg of the wearer.

The shorter arm 18 of the L-shaped frame 3 is provided intermediate its ends and upon one longitudinal edge with an approximately rectangular upstanding heel plate 19 that is formed integral with the arm 18 and adapted to fit snugly about the rear of the heel of the wearer. The bottom of the heel of the wearer is adapted to engage 25 the shorter arm 18 of the support 3 when the device is in assembled position as will be clearly seen with reference to Fig. 2 in the drawings.

Formed integral with the free end of the 30 arm 18 is an upstanding heel plate 20 that is disposed in the same position as the longer arm of the support 3 and adapted to engage the side of the swimmer's heel when the device is in assembled position as illustrated 35 in Fig. 2. The heel plate 20 is provided with an offset portion 21 that is provided with an angularly disposed longitudinal slot 22. A suitable foot strap 23 is inserted through the slot 22 on the offset portion 21 40 and through a slot 24 formed in an ear 25 that is formed on one edge of the longer arm of the support 3 at a point approximately centrally of its lower end and the point where the frame 4 is formed thereon. This 45 strap 23 is adapted to surround the top or instep of the wearer's foot and may be provided with a suitable adjusting buckle 26.

To secure the device to the foot the swimmer places his heel upon the arm 18 so that 50 it is wedged between the longer arm of the support 3 and the heel plate 20 and in bearing engagement with the heel plate 19. The strap 23 is then secured after the manner described across the instep of the wearer's 55 foot and the strap 17 is secured in a similar manner about the lower portion of the swimmer's leg.

In operation, upon the thrusting or working stroke of the swimmer's leg, the paddle 1 60 which is normally disposed in a position in angular relation to the longer arm of the support 3 and so that it will readily move outwardly and engage the water, is moved outwardly upon the stroke, to a position approximately at right angles to the longer

arm of the support 3 and to the leg of the wearer. The arms 5 and 6 which extend to a point approximately centrally of the ends of the paddle 1, engage the paddle and prevent its movement in one direction.

70 It will be readily seen that upon the operation of the device after the manner described, the swimmer may be readily propelled through the water.

It will be apparent that the device, when 75 used after the manner described, affords the use of the swimmer's hands since it is necessary to only slightly move the legs to keep above the water.

It is apparent that the device may be employed to great advantage in saving persons from drowning since the wearer may easily keep afloat and have the use of his hands.

In reduction to practice, I have found that 80 the form of my invention, illustrated in the drawings and referred to in the above description, as the preferred embodiment is the most efficient and practical; yet realizing that the conditions concurrent with the 85 adoption of my device will necessarily vary, I desire to emphasize the fact that various minor changes in details of construction, proportion and arrangement of parts may be resorted to, when required, without sacrificing any of the advantages of my invention, as defined in the appended claims.

90 What is claimed is:—

1. A swimmer's foot paddle comprising a 100 paddle, an L-shaped support adapted to be secured to the foot of the wearer, means for securing the support to the foot of the wearer, a U-shaped frame integral with the longer arm of the support, said paddle being hingedly secured to the U-shaped frame adjacent the inner end thereof beneath the arms of said frame, and spring means for normally holding the paddle in a divergent plane relative to the longer arm of the support.

105 2. A swimmer's foot paddle comprising a support adapted to be secured to the foot of the wearer, a U-shaped frame on said support, a rectangular paddle hingedly secured to said frame beneath the side arms thereof and a coil spring carried by said frame and having its terminals engaging the support and paddle respectively, for holding the paddle in a normal outwardly inclined plane relative to the support.

110 3. A swimmer's foot paddle comprising a support adapted to be removably secured to the foot of the wearer, a frame integral with the support, means for securing the support to the foot of the wearer, a rectangular 115 paddle hingedly secured to said frame beneath said frame, said frame being disposed at right angles to the support and adapted to limit the movement of the paddle to a position of right angular extension and 120 125 130

means for normally holding the paddle in an outwardly inclined plane relative to the support.

4. A swimmer's foot paddle comprising
5 an L-shaped support adapted to be secured to the foot of the swimmer, a frame integral with the support and extending outwardly at right angles thereto, a rectangular paddle hingedly secured to and beneath said frame,
10 said L-shaped support having its longer arm curved outwardly adjacent its upper terminal to conform to the contour of the swimmer's leg, a rectangular cross plate having longitudinal slots in each end formed integral with the upper end of the longer arm of
15 the support, said plate being curved to con-

form to the contour of the swimmer's leg, a strap adapted to surround the swimmer's leg inserted through the slots in the cross plate, the shorter arm of said L-shaped support 20 having a pair of heel plates formed integral therewith, disposed at right angles thereto and to each other and a securing strap secured to one of said ears and to the longer arm of the support adapted to fit over the 25 instep of the wearer's foot.

In testimony whereof I affix my signature in presence of two witnesses.

JOHN W. GOODENBERGER.
